UNITED STATES PATENT OFFICE.

ROBERT H. ENGLE, OF GARDEN LAKE, NEW JERSEY, ASSIGNOR OF ONE-HALF
TO CHARLES W. S. MUNRO, OF PHILADELPHIA, PENNSYLVANIA.

ILLUMINATED SIGN FOR ELECTRICALLY-DRIVEN STREET-CARS.

SPECIFICATION forming part of Letters Patent No. 555,440, dated February 25, 1896.

Application filed March 8, 1895. Serial No. 540,960. (No model.)

To all whom it may concern:

Be it known that I, ROBERT H. ENGLE, a citizen of the United States, and a resident of Garden Lake, Camden county, New Jersey, have invented an Illuminated Sign for Electrically-Driven Street-Cars, of which the following is a specification.

The object of my invention is to provide an illuminated sign for use on electric-railway cars, so that the character of the car can be readily determined at night, and this object I attain in the manner hereinafter set forth, reference being had to the accompanying drawings, in which—

Figure 1 is a longitudinal section of a sign for cars, constructed in accordance with my invention. Fig. 2 is a sectional plan view of the same. Fig. 3 is a transverse section on the line 3 3, Fig. 2. Fig. 4 is an enlarged section of part of the structure. Fig. 5 is a perspective view of other parts of the same, and Fig. 6 is a longitudinal section of a modified form of the device.

In Fig. 1 A represents a casing, preferably of sheet metal, suitably stiffened so as to preserve its form, said casing having at both front and rear a hinged sign-plate B of transparent or translucent material normally retained in position, as shown in Fig. 3, by means of spring-catches a or equivalent retainers.

Within the casing are a pair of electric lamps D D, and at top and bottom of the casing are reversely-inclined reflectors F F retained in position by spring-clips b, so that they can be readily removed for cleansing or repairs.

The casing A has opposite trunnions d adapted to suitable hangers d' depending from that portion of the car-roof which constitutes the hood above the platform, one of the trunnions being provided with a handle d², so that the casing can be readily turned in order to bring either of its sign-plates B to the front, it being usual in street-car signs to employ a double-faced sign, one face indicating the destination of the car when running in one direction and the other indicating its destination when running in the opposite direction.

In order that only the front or outward face of the sign may be exposed the casing A is partially inclosed by a segmental hood G, as

shown in Fig. 3, this hood extending throughout the entire length of the sign, as shown in Fig. 2, and serving, also, to reflect back into the casing any light which would otherwise be dissipated in the rear of the same.

The lamps D D are connected in series by means of a wire f, the current entering one of the hangers d' and passing thence through the trunnion to one of the lamps D, from the latter through the wire f to the other lamp, and from the latter through the opposite trunnion and hanger d' to the line.

Each of the trunnions is insulated from the casing of the sign, as shown in Fig. 4, by insulating material h interposed between the trunnion d and the casing, and also between the latter and the nuts i i', whereby the casing is secured to the trunnion.

On one of the trunnions d of the sign is a collar or sleeve m, having beveled toes m' which enter recesses in the adjoining bearing d', the collar being acted upon by a spring m² tending to project it and being prevented from turning on the trunnion by means of a pin 75 m³ on the latter entering a slot in the collar.

When power is applied to the handle d² to turn the sign, the collar m will be pushed backward and the toes will travel on the inner face of the bearing d' until they reach 80 the opposite notches, into which they will be projected by the spring m², so that there is no likelihood of the sign being turned more than half-way around at one time, nor is there any possibility of the sign being accidentally 85 moved from its proper position by the shaking or jarring to which it is subjected.

The use of the inclined reflectors in the upper and lower portions of the casing A serves to insure the uniform and thorough lighting 90 of all parts of the sign-plates B, since the latter are illuminated not only by the rays passing directly outward from the lamp, but also by those rays which pass upward and downward and are reflected outward by the inclined mirrors. Hence the full lighting effect 95 of each lamp is availed of for the illumination of the sign-plates.

In Fig. 6 I have illustrated a modified construction of sign in which the casing A is 100 hung upon a vertical pivot instead of upon horizontal pivots. In this case the handle

stem or shaft n at the bottom of the sign has a cross-head n' , provided with rods n^2 , which pass through openings in the longitudinal brace-bar J at the top of the casing and are connected at the upper end to a collar p , acted on by a spring p' and having toes p^2 , engaging with recesses in a depending hanger K . Through this hanger pass a rod s and a tube s' , insulated from each other and from the hanger, the tube being connected to one line-wire and the rod to the other. The rod projects inwardly beyond the tube, so as to provide for the use of contact brushes or fingers $t t'$, the finger t bearing upon the rod and the finger t' upon the tube, as shown, and said finger t is connected to one of the lamps D by a wire x , the finger t' being connected to the other lamp D by a wire x' , and the lamps being connected by a wire x^2 , so that the lamps are connected in series.

In all cases I use lamps having narrow cylindrical bulbs of a diameter but little in excess of the incandescent loop or filament of the lamp, so that I am enabled to very materially contract the lateral dimensions of the sign-casing as compared with signs having lamps with the usual pear-shaped bulbs, and I am also enabled to correspondingly contract the height or vertical dimensions of the sign-casing by bringing the upper and lower reflectors closer together than would be possible if a pear-shaped bulb was used, so that the said upper and lower reflectors can be disposed at the proper angles for reflecting the light through the sign-plate without unduly increasing the vertical dimensions of the casing.

It will be evident that by my invention the annoyance now caused by the difficulty of deciphering at night the signs carried by street-cars will be effectually overcome.

My invention may, as will be evident, be embodied in a sign having but one lamp or more than two, as well as in a casing having but one sign-plate or more than two, the construction shown, however, being preferred.

Having thus described my invention, I claim and desire to secure by Letters Patent—

1. The within-described illuminated sign for street-cars, the same consisting of a casing having in one or more of its sides a translucent or transparent plate and having a lamp with narrow cylindrical bulb projecting longitudinally into the casing from either end, means for mounting said casing, and reflectors extending longitudinally through the casing above and below the lamp, these reflectors being in a horizontal plane longitudinally, but inclined transversely and the opposed upper and lower reflectors being reversely inclined, substantially as specified.

2. An illuminated sign for street-cars, consisting of a casing having in one or more of its sides a transparent or translucent sign-plate, an electric lamp projecting longitudinally into said casing from either end of the same, means for mounting the casing, reflectors disposed longitudinally in the casing above and below the lamp, and each consisting of a straight flat strip or plate of reflecting material, inclined supports or backings for said plates, and spring-clips whereby the plates are detachably confined to said supports, substantially as specified.

In testimony whereof I have signed my name to this specification in the presence of two subscribing witnesses.

ROBT. H. ENGLE.
